[57] CLAIM

The ornamental design for the storage container for a pick-up or the like, as shown and described.

DESCRIPTION

FIG. 1 is a front perspective view of a storage container for a pick-up or the like showing my new design;
FIG. 2 is a rear perspective view thereof;
FIG. 3 is a fragmentary front elevation thereof;
FIG. 4 is a left side elevation thereof, the right side elevation being a mirror image thereof;
FIG. 5 is a fragmentary sectional view taken along line 5—5 of FIG. 3;
FIG. 6 is a fragmentary sectional view taken along line 6—6 of FIG. 3;
FIG. 7 is a front perspective view of a modified form of FIG. 1;
FIG. 8 is a rear perspective view of FIG. 7;
FIG. 9 is a fragmentary front elevation of FIG. 7;
FIG. 10 is a left side elevation of FIG. 7; the right side elevation being a mirror image;
FIG. 11 is a fragmentary sectional view taken along line 11—11 of FIG. 9; and
FIG. 12 is a fragmentary sectional view taken along line 12—12 of FIG. 9.
